UNITED STATES PATENT OFFICE.

ROBERT J. SEVEREN, OF CHICAGO, ILLINOIS.

PRINTER'S QUOIN.

1,324,773.

Specification of Letters Patent.

Patented Dec. 9, 1919.

Application filed May 26, 1919. Serial No. 299,751.

To all whom it may concern:

Be it known that I, ROBERT J. SEVEREN, a citizen of the United States, and a resident of Chicago, in the county of Cook and State 5 of Illinois, have invented certain new and useful Improvements in Printers' Quoins; and I do hereby declare that the following is a full, clear, and exact description thereof, reference being had to the accompanying 10 drawings, and to the characters of reference marked thereon, which form a part of this specification.

This invention relates to improvements in printers' quoins adapted for locking printing forms in chases. The invention refers 15 more particularly to improvements in printing quoins, which when adjusted to firmly lock the form in the chase, are sufficiently flexible to maintain the locking pressure in 20 the event of slight shrinkage of the form; to improvements whereby the quoin members may separate upon shrinkage of the form without liability, however, of the quoin members shifting laterally relatively to each other 25 so as to fall or jump out of the chase, and to improvements whereby the quoin members may be locked firmly together in adjusted 30 positions by suitable self locking mechanism which permits them to be moved endwise in both directions relatively to each other to 35 lock or release the form without necessity of manually releasing the locking means.

The invention consists in the combination and arrangements of the parts shown in the 35 drawings and described in the specification and is pointed out in the appended claims.

In the drawings,

Figure 1 is a side elevation of a printer's 40 quoin embodying my invention.

Fig. 2 is a longitudinal section thereof on the lines 2—2 of Figs. 3 and 4.

Fig. 3 is a transverse section on the line 3—3 of Fig. 2.

Fig. 4 is a face view of one of the quoin 45 members.

Fig. 5 is a fragmentary view showing the quoin members slightly separated.

The quoin comprises two members 10, 10 of usual form, the outer straight side faces 50 of which are parallel and the inner faces of which are tapered and fit upon each other in such manner that relative endwise movement of the members varies the overall width of the quoin.

The quoin members are provided on their tapered faces with longitudinal central ribs

11 which bear against and slide upon each other. At the wider ends of said quoin members said ribs are flanked by lugs 12, thereby forming between them guide recesses 60 14 for the ribs 11 to maintain said ribs always parallel. The said ribs are formed at the narrower ends of the quoin members with short longitudinal recesses or notches 15 and the quoin members are provided at 65 the sides of the ribs, and below the planes of the bearing faces of the ribs, with key lugs 16 of usual formation to coöperate with the usual quoin operating or adjusting key.

Referring now to the self locking mechanism constituting the present invention, the 70 same is made as follows:

The rib 11 of each quoin member is provided on its inner flat bearing face with a plurality of closely spaced shallow depressions or sockets 17 which extend throughout the principal length of the rib, beginning at the recess 15 at the narrower end of the member. Each rib is also provided adjacent its wider end and in line with the depressions 17 with an opening 18 to receive a locking pin 19. Said locking pin is formed at one end with a head and is rounded at its other end to engage the shallow sockets or depressions 17 of the other member. The 80 locking pins are urged inwardly beyond the bearing faces of their associated ribs by spiral expansion springs 19', seated in said openings 18, said expansion springs bearing upon the headed ends of the pins, being retained in place by studs 20 that are threaded into the outer ends of the openings 18. The inner ends of the openings 18 are reduced and the locking pins fit closely therein, while the outer ends of said openings and the 90 shoulders in said openings between the larger and smaller diameters thereof serve as a means to limit the total inward movement of the pins under the action of the spring.

In operation, the quoin members are assembled with the inner opposing tapered faces of the ribs facing toward or in contact with each other and with the end of the rib at the narrow end of each quoin member entered into the recess 14 at the wider end of the other quoin member. The assembled quoin is placed between the furniture in the chase in the usual manner and the quoin members are shifted endwise relatively to 105 each other by the use of a quoin key engaging the lugs 16 to increase the overall width 110

of the quoin and to thereby lock the form in the chase. As the quoin members are thus adjusted endwise relatively to each other, the locking pins 19 of each quoin member successively pass over and engage the shallow depressions or recesses 17 of the other quoin member until the final locking position is reached, in which position the pins 19 engage their proper sockets to prevent endwise displacement of the members in a direction to release the locks. By reason of the fact that the ends of the pins are rounded and that the bottoms of the recesses 17 are correspondingly rounded and the recesses are shallow, it will be apparent that said pins will automatically pass from one locking recess or depression to the other, regardless of whether the quoin members are being adjusted to lock the form or to release it. Thus it becomes unnecessary to manually release said locking pins when a form is to be unlocked for removal or when it is to be released.

The springs 19 are made of considerable strength so that in the event of a shrinkage of the form such as may occur due to the spring of certain type metal, or to the materials used, as when the form contains electrotype cuts, and also to imperfect justification, the quoin members are permitted to slightly separate, and, at the same time proper locking tension is maintained on the form to prevent the quoin from jumping out of place and releasing the locking pressure. This lock retaining action of the quoin is due to the engagement of the rounded ends of the locking pins with the like shaped sockets 17 which serve, not only to self center the pins in their sockets, but also to prevent relative lateral movement of the quoin members and to the follow up action of the springs. It is necessary that the forms be locked under such tension that they will be reliably held in the chase under all practical working conditions but it is objectionable that the tension be so great as to tend to cause the form to spring upwardly under the vibration of the press or under the action of the press cylinder. In the construction described it becomes possible to regulate the locking tension of the quoins on the forms to avoid tendency of the forms buckling and also to maintain the desired tension in the event of shrinkage of the forms for any reason. There are many reasons why quoins work loose relatively to the forms, such, for instance, as locking one pair of quoin members tighter than another, which will cause one or more quoins to work loose as the form sets, and in many cases the vibration of the press will cause said quoins to work loose if they have not the proper tension. The construction herein shown is such as to cause the quoins to equalize and maintain their ten-

sion on the form in the event that the quoins are locked with variable tension or in the event that vibration of the press should tend to cause them to work loose. This feature of the quoin construction is of great importance inasmuch as the loosening of forms in the press often causes great damage to the press cylinder and other parts of the press.

Another feature of advantage of the construction described is the formation of the ends of the locking pins and their co-operating recess or depression whereby the said pins will ride from one recess or depression to the other without manually releasing the locking pins, such as would occur in one direction or adjustment if an ordinary pawl or ratchet locking mechanism be employed. Thus the quoins may be quickly released or unlocked inasmuch as all that is required to unlock the quoins is the usual locking action of the locking key. Such releasing of the quoins is often required a great many times in locking up a form in order to correct the register of pages, et cetera, so that the automatic release becomes an important factor in the time saved. Furthermore, the self locking feature avoids the likelihood of the pressman forgetting to lock the quoins when once set.

It will be understood that said recesses or depressions 17 are closely spaced so as to permit finely graduated adjustments of the quoin members and the form of the coacting pins and sockets insures self centering of the pins in the sockets.

In order that the person using the quoin may know when the locking pins are seated in their sockets or depressions 17, one or both of said quoin members are provided with a series of short transverse gage marks which are adapted to register with other gage marks 22 at the wider ends of the quoin members, as most clearly shown in Fig. 1. The gage marks 21 are so spaced relatively to the spaces of the centers of the sockets or depressions 17 that when a gage mark 21 of one member is in line with the gage mark 22 of the other member, it will be known that the locking pins are seated in and interlocked with the proper sockets or depressions 17.

I claim as my invention:

1. Printer's quoin comprising endwise relatively movable members having tapered coacting faces, said members being provided at said coacting faces with locking means spring actuated in a direction transverse to said faces and operable to permit endwise movement of said members in both directions.

2. Printer's quoin comprising endwise relatively movable members having tapered coacting faces, said members being provided at said coacting faces with self centering

locking means, spring actuated in a direction transverse to said faces permitting endwise movement of said members, when so locked, in both directions.

5 3. Printer's quoin comprising endwise relatively movable members having tapered coacting faces, said members being provided at said coacting faces with closely spaced,

shallow, round bottom recesses and with spring-pressed, round ended pins to engage 10 said recesses.

In witness whereof I claim the foregoing as my invention, I hereunto append my signature at Chicago, Illinois, this 23rd day of May, 1919.

ROBERT J. SEVEREN.
